FRAME FOR VENDING MACHINES

Elmer C. Johnson, Kansas City, Mo., assignor to The Vendo Company, Kansas City, Mo., a corporation of Missouri

Application December 8, 1958, Serial No. 53,674

Term of patent 14 years

(Cl. D52—3)

Fig. 2.

Fig. 1.

Fig. 1 is a front perspective view of a frame for vending machines, showing my new design; and

Fig. 2 is a rear perspective view of the frame for vending machines, in an open condition.

The undisclosed side of the frame for vending machines is substantially plain. The vending machine depicted in broken lines is for illustrative purposes only.

I claim:

The ornamental design for a frame for vending machines, as shown and described.
